UNITED STATES PATENT OFFICE

WELLS H. CLAUSSEN, OF SEATTLE, WASHINGTON, ASSIGNOR TO APPLE VENDER CO.,
OF SEATTLE, WASHINGTON, A CORPORATION OF WASHINGTON

DESIGN FOR A CASING FOR FRUIT VENDING MACHINE

Application filed February 24, 1931. Serial No. 38,802. Term of patent 14 years.

To all whom it may concern:

Be it known that I, WELLS H. CLAUSSEN, a citizen of the United States, residing at Seattle, in the county of King and State of Washington, have invented a new, original, and ornamental Design for Casing for Fruit Vending Machine, of which the following is a specification, reference being had to the accompanying drawings, forming a part thereof.

Figure 1 is a front view of the article in isometric perspective, showing my new design.

Figure 2, is a side view of the article on a reduced scale with respect to that of Figure 1.

I claim:

The ornamental design for a casing for fruit vending machine, as shown.

WELLS H. CLAUSSEN.
